UNITED STATES PATENT OFFICE.

GEORGE B. SIPE, OF SHREVEPORT, LOUISIANA.

METHOD OF PRODUCING SUBAQUEOUS FOUNDATIONS, PIERS, BREAKWATERS, ETC.

Application filed November 3, 1923. Serial No. 672,538.

The present invention relates to methods of producing supports, such as piers, and structures, such as breakwaters, where the prevailing water has to be taken into consideration, as along the sea and lakes, in rivers and streams, and swamps, and wherever water is encountered which makes difficult the removal of earth, rock, etc., and the placing of structural material such as concrete as a firm support for superstructures and formations to resist the encroachments of the sea.

The present invention, while incorporating therein some or all of the steps set forth in my co-pending application for Letters Patent on methods of producing and placing piles, filed October 26, 1923, and bearing Serial Number 671,015, may be distinguished therefrom in that it makes possible, by added or substituted steps, the use of such method where water prevails and where it is desirable to provide structures of very large dimensions in the water and extended therefrom, but having a firm bearing upon bed rock below the water bottom, and subaqueous formations of compressible character.

Among the principal objects of the present invention is the provision of methods whereby piles of concrete or its equivalent, either plain or reinforced, may be provided in the formations below bodies of water, extended to bed rock, terminating at any point desired, such as adjacent the more solid formation directly beneath the muddy bottom of the body of water, in the mud or water, or above the high water level, it being possible to accomplish this, laying the concrete "in the dry" if desired, in contra-distinction to depositing the concrete through water which is not so strong. Such piles may be used to support superstructures, such as piers, dams, wharves, etc., or used as a sea wall, starling, breakwater, or as a part of a quay.

Another object of the invention is to provide a method by which structures of considerable magnitude, such as dams, piers for bridges, piers extending into navigable water, foundations for warehouses, light houses and other buildings may be placed on and have incorporated therein piles extending to bed rock, regardless of its depth from the surface and the number and character of intervening strata.

A further object of the invention is to provide methods by which such construction

may be carried on with exactness, expeditiously and economically and without resorting to the use of pneumatic caissons, cofferdams, or other apparatus which require workmen to go down into cavities exposed to hazard.

In carrying out the present method use may be made of the principle embodied in rotary drill apparatus which has proven successful in the drilling of oil wells in which connection reference may be had to United States Patents No. 1,360,328 and 1,379,483 and 1,451,794, granted November 30, 1920, May 24, 1921, and April 17, 1923, respectively on the inventions of John C. Stokes. Such apparatus comprises a hollow drill stem for imparting a rotary movement to a collapsible bit, which bit, in its working position is supported by a drill collar or holder in such a manner that the bit may cut a hole substantially twice the diameter of the drill stem, yet may be withdrawn and replaced through the stem when such is desired.

Other objects and advantages of the invention will appear in the following detailed description, forming a part of this specification, taken in connection with the accompanying drawings, and in which drawings:

Figure 1 is a view partly in central vertical section and partly in elevation showing an initial step in the method of providing and placing a pile beneath the water.

Fig. 2 is a cross sectional view on the line 2-2 of Figure 1.

Fig. 3 is a central vertical view through the finished pile, which, in the example shown is terminated adjacent the water body bottom.

Fig. 4 is a plan view of a floatable caisson or conductor, which may be used in the production of a pier or similar unit.

Fig. 5 is a diagrammatic view showing in full lines a plurality of hollow cylindrical caissons sunk into the water body bottom upon which the floatable caisson may be brought to rest, such floatable caisson being shown in dotted lines.

Fig. 6 is a view partly in elevation, vertical section and perspective showing the floatable caisson about in readiness to be sunk or lowered to a position upon hollow caissons which have been previously sunk.

Fig. 7 is a view partly in vertical section and partly in elevation showing the caisson

or conductor partly linked with the bed rock and showing apparatus which may be used in carrying out the process in course of operation.

5 Fig. 8 is a view similar to Figure 1 showing a method which is particularly well adapted to use for placing a pier or similar structure where the bottom of the water body is very uneven.

10 Fig. 9 is a fragmentary view in elevation showing the lower removable portion of a conductor used in such method.

15 Fig. 10 is a central vertical sectional view through a finished pile formed and placed by use of the conductor.

20 Fig. 11 is a view partly in elevation and partly in vertical section, showing parts of a pier in operative relation for linking of the major portion to bed rock.

25 Fig. 12 is in the drawings, where like characters designate similar or corresponding formations or parts, the letter A designates a body of water, such as the sea, a lake or river; B the muddy bottom which usually prevails beneath the water; C more firm yet compressible soil or formation subjacent to the body of water, aptly termed "terra firma"; and, D bed rock, the distance of which beneath the body of water, and formation subjacent thereto, varies in different localities.

30 In order to more readily distinguish a caisson or caissons which are primarily intended to act as conductors or guides for certain apparatus and materials used in placing piles, from hollow casings which may follow the drill, as referred to in my aforesaid application for Letters Patent, the letter E is used to designate such caissons and to apply the term "conductors" thereto in 35 this specification, where such are used to exclude the sea or other water to facilitate operation of apparatus and to permit, when desirable, the placing of concrete "in the dry". The letter F designates suitable drilling apparatus capable of producing a cavity G; and H the hollow casing, above referred to, which may follow the drill as it penetrates the soil and various strata, to the bed rock.

40 In my aforesaid application for Letters Patent is set forth more in detail the manner in which rotary drill apparatus may be utilized for penetrating the various strata encountered when drilling a cavity to firm or bed rock and therefore it suffices to state, at the present time, that the drilling apparatus F comprises a rotary drill stem 12 and collapsible bits 13 which may be caused to rotate and descend in unison, the bits 13 being removable through the drill stem, in a manner well known in the art relating to drilling apparatus, and in which connection reference may be had for an example, to U. S. Patents No. 1,360,328 and 1,379,483.

45 Such bits may also be returned to an opera-

tive position, or different bits utilized, without the necessity of withdrawing the drill stem 12 when placing or removing a bit.

50 In Figures 1, 2, and 3 may be found an illustration of the present method which enables the cavity G to be provided, excluding the sea or water from the cavity and permitting the mud which is used to assist in drilling, to be introduced downwardly through the drill stem, then outwardly adjacent the cutting portion of the bits 13, and then upwardly through the hollow casing H and caisson E, which mud may be reused by being pumped from and into a suitable sump, not shown in the drawings. The caisson E also permits of the removal of the water from the cavity used in flushing the cavity free of mud and loose particles, thus permitting the concrete to be placed "in the dry", when such is desired.

55 Initially, the caisson E, having a way 14, is transported, in any suitable manner, such as by means of a boat or barge to the point where the pile is to be provided, and the caisson is sunk so that its open upper end portion is above the water, and its lower end portion in the terra firma C subjacent to the body of water A. In some instances it may not be necessary to sink this caisson entirely through the muddy bottom B, in order to prevent the inrush of the sea, or water, when the cavity is drained of water for the purpose of introducing concrete into the cavity as heretofore referred to. The drill stem 12 with bits 13 in operative relation thereto, is then lowered through the way 14, and by imparting rotary motion to the stem 12 and introducing water or mud, as hereinbefore mentioned, the cavity G may be provided in substantially the same manner as is obtained by practicing the method set forth in my aforesaid application for patent. The hollow casing H may be lowered, so as to follow the drill where the formation C is not self sustaining, so to speak. When the hollow casing H is used, it may be withdrawn as the cavity G is filled with concrete, or it may be permitted to remain in the cavity, as shown in Figure 3. Suitable reinforcements 15 may be introduced into the cavity before disposing the concrete therein, and in Figure 3 is disclosed, by means of a central vertical sectional view, a finished pile 16, the upper portion of which is shown as terminating in the muddy bottom B, but may terminate therebelow, in the water A, or extended above the surface of the water, depending upon the use for which the pile is intended.

60 This pile may be used to aid in supporting a superstructure, or act as a part of a jetty, to influence the current or tide, or to protect a harbor, or may form a part of a starling, disposed around the piers of bridges, for protection thereof. Such piles

may be disposed in close proximity to one another, acting as a sea wall, or break water. Where the pile terminates below the surface of the water, the caisson E may be removed, and used a number of times for the purpose specified.

When it is desired to provide a structure of considerable magnitude, such as a pier extending into navigable water and of a size to have a road way, or a promenade, on its top, and perhaps warehouses, and the bottom of the body of water is comparatively level, the caisson E' may be formed of reinforced concrete, of considerable size and capable of being floated to the site where it is to be disposed. In this connection reference may be had to Figures 4, 6 and 7, where the caisson E' is shown as comprising a bottom 18, side walls 19, end walls 20 and a plurality of conductor tubes 21 projecting upwardly from the bottom 19 into a chamber 22 formed by the bottom 18 and side and end walls 19 and 20, respectively. The walls 19 and 20 as well as the conductor tubes 21 may be provided with laterally spaced apart vertical conductor ways 23 extending therethrough, similar to the way 14. A temporary filling or closure 24 may be disposed in the lower portion of the conductor ways 23, such as a partition of neat cement, so as to exclude water from these ways as the caisson E' is being floated, thus adding to the buoyancy thereof.

In order to provide a firm support for the caisson E' so that it may be linked with the bed rock subjacent to the body of water in which the pier is to be disposed, hollow piles 25 are disposed in laterally spaced apart relation as shown by the full lines in Figure 5, so as to terminate in substantially the same plane as the upper surface of the formation C, as shown in Figure 6. Such piles may be placed by use of the rotary drilling apparatus F and may be of such length as to initially support the caisson E', by friction of the piles with respect to the more firm formation C.

The caisson E' having been constructed either on the land and launched, or in the sea, is floated, as by means of barges, and tugs until positioned above the piles 25, whereupon the caisson E' may be caused to settle upon the piles, such as by breaking the temporary closures 24, thus reducing the buoyancy of the caisson. The piles 25 may be spaced apart a predetermined distance, so that they may axially align with certain of the conductor ways 23. Only a sufficient number of piles 25 need be initially disposed in the formation subjacent to the body of water for the purpose of supporting the caisson which settles thereupon, during the operation of linking the caisson with the bed rock D. The weight of the caisson may be sufficient to cause it to settle through the

muddy bottom B, or water may be introduced, under pressure, through the conductor ways in order to disturb the muddy bottom adjacent the caisson, in order to cause such settlement.

In Figure 7 is shown drilling apparatus F which has been guided downwardly through one of the conductor ways 23, through the hollow pile 25 and penetrating the lower portion of the formation above bed rock D, thus producing a cavity G in such formation C. This figure also discloses completed piles 26 which extend from the bed rock upwardly through hollow piles 25, and into certain of the conductor ways 23. This figure also shows drilling apparatus F guided through one of the conductor ways 23, beneath which no hollow pile 25 has been disposed, it being obvious from the drawings that each conductor way may be utilized to facilitate the drilling of cavities through the formation C subjacent to the body of water A, and extending into the bed rock D, and that these conductor ways may also receive a filling containing cementitious material which is introduced, first in the bottom of the cavity, and then added to, until the entire cavity and conductor ways contain such filling, which may be reinforced, if desired, in any approved manner.

In Figure 5 there is diagrammatically represented, by dotted lines, the position of the caisson E', shown in Figure 4 and indicating that many of the piles which link the caisson with the bed rock need not be extended through hollow piles 25, primarily disposed in the formation C. By causing the caisson E' to come to rest, settled in the muddy bottom B, less effort is required to retain the caisson in place, properly aligned with respect to the piles 25, against currents which may prevail in the body of water A.

Where a pier is to be provided in water, the bottom of which is not substantially level—conditions usually met in connection with the erection of bridge piers, piles 27 may be initially produced and placed in the formation C and extending into bed rock D, with their upper end portions in substantially the same plane and terminating either in the muddy bottom, in close proximity to the more firm formation, or above the muddy bottom, as shown in Figures 10 and 11, by resorting to a modified form of caisson E'', which comprises a major or upper portion 28 and a lower minor portion 29 which is detachable from portion 28, the portion 29 to remain in the formation and form a part of the pile 27. This may be accomplished by the provision of a pair of diametrically disposed lugs 30 adjacent the lower end of portion 28, adapted to fit in bayonet slots 31 formed in the lower portion 29. Each bayonet slot 31 has a longitudinally extending entrance 32 open to the upper margin

of the part 29, a circumferentially extending way 33, leading from entrance 32, and a recess 34 laterally of but spaced from entrance 32, into which the lug 30 may come 5 to rest, in order to effectively support the part 29 at the lower end of portion 28, when the caisson E'' is being lowered into place. It may be desirable to impart rotary movement to the caisson E'' in order that the 10 lower portion may penetrate through the muddy bottom and engage in the more firm formation C. In the example shown in Figure 8 a hollow casing H is shown following the drilling apparatus F, and this hollow 15 casing H may be removed after the drilling apparatus F reaches bed rock, and the cavity G is being filled with concrete, leaving merely the lower portion of caisson E' as a part of the pile. Sufficient concrete may be introduced 20 into the cavity G so that when the hollow casing H is removed, and the upper portion 28 of the caisson E'' is also removed, such concrete will extend flush with the upper surface of the lower portion 29 of the 25 caisson E'' which remains in the bottom of the body of water, as shown in Figure 10 of the drawings.

As may be observed from Figure 11, the caisson E' of considerable magnitude may 30 be caused to settle upon the upper portions of piles 27 in substantially the same manner as described in connection with Figures 4, 6 and 7, and such caisson linked with the bed rock by entering such apparatus as is 35 necessary, through the conductor ways 23 and continuing the filling of the cavities formed by such apparatus, into the conductor ways 23 in exactly the same manner as set forth in connection with Figure 7. The 40 chamber 22 need not necessarily contain conductor tubes as designated by 21 in Figure 4, and the chamber 22 may be filled with concrete or other suitable material, much depending upon the weight coming upon the 45 pier thus formed.

In reduction to practice, I realize that the conditions concurrent with the adoption of the method will necessarily vary, and I desire to emphasize the fact that various 50 changes in the sequence of steps taken in the method may be resorted to, or steps omitted, when required or desirable, without sacrificing the advantages of the method.

While I have herein referred to certain 55 patents relating to rotary drills, and to the method disclosed in my co-pending application for patent, it is to be distinctly understood that such are merely by way of example, and that the methods may be carried 60 out by the use of other apparatus than that herein disclosed and referred to, without departing from the spirit or scope of the appended claims.

I claim:

65 1. A method of producing and placing

piers which comprises, placing a plurality of laterally spaced apart piles extending into the formation subjacent to the body of water in which the pier is to be located; disposing a caisson, having a plurality of laterally 70 spaced apart vertical conductor ways therethrough, upon said piles, said ways being open above the water; drilling cavities open to the conductor ways, through the formation and into the bed rock subjacent to said body of water and removing the dislodged material through said conductor ways; and depositing a filler including cementitious material in the said cavities and conductor ways, to link said caisson to the bed rock. 75

2. A method of producing and placing piers, which comprises, placing a plurality of laterally spaced apart piles extending into the formation subjacent to the body of water in which the pier is to be placed and with 80 tops of the piles in the muddy bottom of the body of water; settling a caisson, having a plurality of laterally spaced apart vertical conductor ways therethrough, upon said piles and with its lower portion embedded 85 in the mud; drilling cavities open to the conductor ways, through the formation and into the bed rock subjacent to said body of water and removing the dislodged material through said conductor ways; and depositing a filler including cementitious material in the said cavities and conductor ways, to link 90 said caisson to the bed rock. 95

3. A method of producing and placing piers which comprises, placing a plurality of laterally spaced apart piles extending into the formation subjacent to the body of water in which the pier is to be placed and with the tops of the piles in the muddy bottom of the body of water; floating a buoyant 100 caisson, having a plurality of laterally spaced apart vertical conductor ways therethrough but temporarily closed at their lower portions to add buoyancy to the caisson, to a position above the piles; removing 105 the temporary closures of the conductor ways and settling the caisson upon said piles with its lower portion embedded in the mud; drilling cavities open to the conductor ways, through the formation and into the bed rock 110 subjacent to said body of water and removing the dislodged material through said conductor ways; and depositing a filler including cementitious material in the said cavities and conductor ways, to link said caisson to the bed rock. 115

4. A method of producing and placing piers which comprises, placing a plurality of laterally spaced apart piles extending into the formation subjacent to the body of water 120 in which the pier is to be placed and with the tops of the piles in substantially the same plane below the level of the water; settling a caisson, having a plurality of laterally spaced apart vertical conductor ways 125

therethrough, upon said piles with the conductor ways offset with respect to the piles; drilling cavities open to the conductor ways through the formation and into the bed rock 5 subjacent to said body of water and removing the dislodged material through said conductor ways; and depositing a filler including cementitious material in the said cavities and conductor ways, to link said caisson to the bed rock.

5. A method of producing and placing piers in a body of water having an uneven or sloping bottom which comprises disposing a hollow caisson having its lower end portion separable from its upper end portion, in the body of water with its upper end open above the water and its lower end extending through the muddy bottom, and into the firm formation subjacent to the body 15 of water; drilling a cavity open to the caisson through the formation and into the bed rock subjacent to the body of water and removing the dislodged material through said caisson; disposing a filler including cementitious material in the cavity and the lower portion of the caisson; removing the upper portion of the caisson, leaving the lower portion extending through the muddy bottom to act as a form for the cementitious material; again disposing the upper portion 20 of the caisson with a different separable lower portion in the body of water and repeating the procedure to produce a plurality of laterally spaced apart piles terminating adjacent the firm formation subjacent to the body of water; disposing a caisson, having a plurality of laterally spaced apart vertical conductor ways therethrough, upon said piles, said ways open above the water; drilling 25 cavities open to the conductor ways, through the formation and into the bed rock

subjacent to said body of water and removing the dislodged material through said conductor ways; and depositing a filler including cementitious material in the said cavities and conductor ways, to link said last mentioned caisson to the bed rock. 45

6. A method of producing and placing piers which comprises, placing a plurality of laterally spaced apart piles extending into the formation subjacent to the body of water in which the pier is to be located; settling a caisson having a large chamber open on the caisson at its upper portion and a plurality of laterally spaced apart vertical ways therethrough, upon said piles; drilling cavities open to the conductor ways through the formation and into the bed rock subjacent to said body of water and removing the dislodged material through said conductor ways; and disposing a filler including cementitious material in the said cavities, chamber and conductor ways. 50 55

7. Those steps in the method of producing subaqueous foundations which consist of disposing a hollow caisson having its lower end portion separable from its upper portion, in the body of water with its upper end open above the water and its lower end extending through the muddy bottom and into the firm formation subjacent to the body of water; drilling a cavity open to the caisson through the formation and into the bed rock subjacent to the body of water and removing the dislodged material through said caisson; disposing a filler including cementitious material in the cavity and lower portion of the caisson; and removing the upper portion of the caisson, leaving the lower portion extending through the muddy bottom to act as a form for the cementitious material. 60 65 70 75

GEORGE B. SIPE.
